TIME-STAMP.

1,320,355.

Specification of Letters Patent.

Patented Oct. 28, 1919.

Application filed May 15, 1919. Serial No. 297,233.

To all whom it may concern:

Be it known that I, SIMON AGRANAT, a citizen of the United States, residing at Chelsea, in the county of Suffolk and State 5 of Massachusetts, have invented new and useful Improvements in Time-Stamp, of which the following is a specification.

This invention relates to a stamp adapted to print an impression indicating the time 10 when the impression was printed. A stamp of this character in common use includes a time piece, such as a watch, having printing means projecting from its back and including a printing member coaxial with the hour 15 hand, and adapted to be rotated therewith, and another printing member adapted to be revolved about the axis of the hour hand and having the same rate of movement as the minute hand. The two members, which 20 are usually of rubber, coöperate with a printing pad of the same material, said members and the printing pad being flush with each other, so that they are adapted to be pressed simultaneously against an inking 25 pad to receive ink, and against a sheet of paper to print an impression which indicates the time when it was made. Heretofore the time piece and printing pad have been carried by a holder which is merely a 30 body having a handle, the whole constituting a hand stamp which is grasped by the operator and pressed alternately against an inking pad and a sheet of paper. In thus operating the stamp the operator is liable 35 to injure delicate parts of the time piece by too energetic manipulation both in inking and in printing. Moreover, the operator is quite likely to lay the stamp down with the time piece in a horizontal plane. This position long maintained is detrimental to a 40 watch movement, as is well known by watch makers.

My invention has for its object, first, to prevent liability of leaving the time piece 45 in a horizontal position when the stamp is not in use, and secondly, to minimize liability of injury to the time movement by rough handling.

To these and other related ends the invention consists in the improvements which 50 I will now proceed to describe and claim.

Of the accompanying drawings forming a part of this specification,—

Figure 1 is an end elevation of a time stamp 55 embodying my invention.

Fig. 2 is a side elevation of the same.

Fig. 3 is a section on line 3—3 of Fig. 1, the time piece being shown in elevation.

Fig. 4 is a section on line 4—4 of Fig. 2.

Fig. 5 is a perspective view of the case, 60 the time piece being removed.

Fig. 6 is a fragmentary perspective view showing a portion of the inner section of the case.

Fig. 7 is an enlarged view showing the 65 outer ends or printing faces of the printing members controlled by the time piece.

Fig. 8 represents a typical impression printed by the stamp.

The same reference characters indicate the 70 same parts in all of the figures.

The stamp includes a supporting structure, preferably composed of a base 12, and two standards 13 fixed to the base and perpendicular thereto.

The base is provided with an impression bed 14 which is preferably of sheet rubber. With the standards 13 is engaged in any suitable way an inking pad 15, which is perpendicular to the bed 14.

17 represents the exterior of a time piece, such as a watch, of any suitable construction, the watch being adapted as usual for use in a time stamp by a printing member 18, attached to an arbor 19 rotated by the 85 watch mechanism, and a printing member 20 attached to an annular disk 21 surrounding the arbor 19, and also rotated by the watch mechanism, the member 18 rotating with the hour hand, and the member 20 revolving 90 about the member 18 and moving with the minute hand. The said printing members, which are preferably of rubber, project from the back of the watch as shown by Fig. 3, and constitute a well known time-indicating 95 printing means adapted to coöperate with a printing pad 23 in printing an impression, such as that shown in Fig. 8.

The time piece is removably inserted in a movable case, which constitutes a carrier 100 for the printing pad 23, and for the printing members 18 and 20, and is adapted to press said pad and members either against the inking pad 15, or against a sheet of paper on the impression bed 14.

105 The case is preferably composed of an inner section 24, and an outer section 30, slideable on the inner section. The inner section 24 has a flat back in which is an opening 26, through which the printing members 110

18 and 20 project, the printing pad 23 being cemented, or otherwise secured to said back, and preferably provided with an opening 27 registering with the case back opening 26. 5 The outer section 30 has a larger opening 31, through which the dial of the time piece is visible, and screw holes receiving screws 32 engaging tapped sockets 34 in the section 24, the screws when turned inward 10 drawing the sections together and causing them to bear on opposite sides of the time piece. Each section has a seat for one side of the time piece, as indicated by Fig. 3, one seat bearing on the inner side, and the other 15 seat on the outer side of the time piece. The means, embodied in the screw holes 34 and the screws 32, for adjustably connecting the sections, enable said seats to positively clamp the time piece. Provision is thus made for 20 holding time pieces of different thicknesses, and for adjusting the inner sections to cause the printing pad 23 to bear evenly on the inking pad and on the impression bed. The sections 24 and 30 are provided with coinciding slots 36 and 37, through which the 25 time piece stem 38 passes. The means whereby the case is adapted to press the printing pad and printing members alternately against the inking pad and paper on the impression bed, is preferably embodied in the 30 connections next described, between the case and the supporting structure.

To opposite ends of the outer case section 30 are attached oppositely projecting alined 35 trunnions 40 (Fig. 5). The standards 13 are provided with alined studs 41, on which are pivoted two levers 42, which are connected at their outer ends by a cross-bar or handle 43. The case trunnions 40 are journaled in 40 bearings in the levers 42, between the pivoted and swinging ends of the levers.

To the front case section 30 is fixed an arm 44 having a slot or groove 45. Mounted on a fixed arm 46 on one of the standards 13, 45 is a stud 47 which enters the slot in the case arm 44. The arrangement of the above-described parts constituting said connections is such that when the levers 42 are raised to the full line position shown by Fig. 2, the 50 case and the time piece are held in a vertical plane, and the printing pad and the time-indicating printing members of the time piece are pressed against the inking pad. When the levers are swung forward and 55 downward to the dotted line position shown by Fig. 2, the case and time piece are caused to turn on the axis formed by the trunnions 40 and their bearings in the levers, the case and time piece being given a quarter of a 60 full rotation, and the printing pad and the time-indicating printing members are pressed against paper previously deposited on the impression bed 14.

It will now be seen that the time piece is 65 moved in a predetermined path to the ink-

ing and printing positions, and is arrested in said positions without injurious shocks or jars, so that the pivots and other delicate parts of the time piece are not liable to injury. It will also be seen that when the 70 stamp is not in use, the time piece stands at one end of its path of movement, with its dial in a substantially vertical plane, a position which is recognized by watch makers as the most advantageous. After an impression 75 has been printed, the operator in removing the printing pad from the paper on the impression bed, naturally moves the case and time piece to the vertical position shown by full lines in Fig. 2, the inking pad acting 80 as a stop to arrest the case and the printing pad carried thereby with the dial of the time piece in a substantially vertical plane, the time piece remaining in this position until the stamp is again operated. The operator 85 cannot, therefore, carelessly leave the time piece with its dial in a substantially horizontal plane, a position which is well known to be detrimental.

The printing pad 23, and the impression 90 bed 14 constitute yielding buffers which cushion the time piece when it reaches each extreme of its movement. Said pad and bed are preferably composed of rubber having air cells, the cells of the pad 23 being 95 shown at 49 in Fig. 3. This cellular structure increases the cushioning effect, as will be readily seen. The stud 47 is preferably movable endwise in the arm 46, so that it may be withdrawn from the slotted arm 44 100 as a part of the operation of removing the case from the supporting structure, the stud being slidable in a socket 50 attached by a set screw 51 (Fig. 1) to the arm 46. A spring 52 (Fig. 4), yieldingly holds the stud in engagement with the slotted arm 44, and a handle piece or disk 53 on the outer end of the stud enables the stud to be retracted.

The tapped sockets 34 are located at the corners of the inner case section 24, and the screws 32, correspondingly located on the outer case section 30, enable the inner case section and the printing pad to be adjusted as may be required, to secure parallelism of the printing pad with the inking 115 pad and with the impression bed.

The printing pad 23 and the time-indicating printing members 18 and 20 may be adapted to print an impression such as that shown by Fig. 8, the characters 18^a and 20^a 120 being printed by the members 18 and 20, and the other characters by the pad 23, the latter being provided with removable members adapted to print the word "Received" and the date.

The base 12 may be provided with a drawer 12^a to receive the movable type members.

The dial 17^a of the time piece is exposed 125 to view through the case opening 31, when 130

the case and time piece are at each extreme of their movement.

The described provision for disengaging the stud 47 from the slotted arm 44, enables the case and the printing pad to be turned to a convenient position for the insertion and removal of the movable type members.

I claim:

1. In a time stamp, in combination, a time piece having time-indicating printing means projecting from its back, a supporting structure including a base having an impression bed and adapted to rest on a horizontal support with the impression bed in a substantially horizontal plane, and an inking pad fixed to said structure with its acting face perpendicular to the impression bed, a case adapted to hold the time piece and expose the printing means and dial thereof, printing means, carried by the case, and connections between the case and the supporting structure organized to move the case in a predetermined path, the arrangement being such that when the case is at one end of its path of movement, the printing means of the time piece and case are presented to paper on the impression bed, and when the case is at the opposite end of said path, said printing means are arrested by the inking pad, with the time piece dial in a substantially vertical plane.

2. A time stamp embodying the combination specified by claim 1, the case being composed of an inner section carrying a printing pad, and having a seat for one side of the time piece, and an outer section having a seat for the opposite side of the time piece and a dial-exposing opening, means being provided for adjustably connecting said sections and positively clamping the time piece between said seats.

3. A time stamp embodying the combination specified by claim 1, the case being composed of an inner section carrying the printing pad, having a seat for one side of the time piece, and provided with tapped sockets, and an outer section slidable on the inner section, having a seat for the opposite side of the time piece and provided with a dial-exposing opening and with screws engaged with said sockets to adjustably con-

nect the sections and positively clamp the time piece between said seats.

4. A time stamp embodying the combination specified by claim 1, the case being composed of an inner section carrying a printing pad, and having a seat for one side of the time piece, and an outer section having a seat for the opposite side of the time piece and a dial-exposing opening, means being provided for adjustably connecting said sections and positively clamping the time piece between said seats, the said connections comprising a pair of connected levers fulcrumed on the supporting structure, trunnions on the outer section of the case journaled in said levers, a slotted arm attached to the outer section of the case, and a coupling stud on the supporting structure engaging said arm, the inner section of the case being movable independently by the section-connecting means to positively clamp the time piece between said seats, and cause the printing means of the time piece and case to bear evenly on the inking pad and on the impression bed.

5. A time stamp embodying the combination specified by claim 1, the case being composed of an inner section carrying a printing pad, and having a seat for one side of the time piece, and an outer section having a seat for the opposite side of the time piece and a dial-exposing opening, means being provided for adjustably connecting said sections and positively clamping the time piece between said seats, the said connections comprising a pair of connected levers fulcrumed on the supporting structure, trunnions on the outer section of the case journaled in said levers, a slotted arm attached to the outer section of the case, and a coupling stud on the supporting structure engaging said arm, said stud being yieldingly held in its operative position and displaceable to disengage it from the arm, and permit the removal of the case from the supporting structure, and the turning of the case to a convenient position for access to the printing means of the time piece.

In testimony whereof I have affixed my signature.

SIMON AGRANAT.
